(57) **CLAIM**

The ornamental design for a lighting fixture as shown and described.

DESCRIPTION

FIG. 1 is a front, perspective view of a lighting fixture showing our new design;

FIG. 2 is a front view of the lighting fixture;

FIG. 3 is a rear view of the lighting fixture;

FIG. 4 is a left side view of the lighting fixture;

FIG. 5 is a right side view of the lighting fixture;

FIG. 6 is a top plan view of the lighting fixture; and,

FIG. 7 is a bottom plan view of the lighting fixture.

The broken lines in the drawing depict portions of the lighting fixture and form no part of the claimed design.

1 Claim, 3 Drawing Sheets
